US00D964155S

(12) **United States Design Patent** (10) Patent No.: **US D964,155 S**
(45) Date of Patent: **** Sep. 20, 2022**

(54) **NAIL**

(71) Applicant: **Relo-Nail Ltd.**, Sofia (BG)

(72) Inventors: **Petar Bodurov**, Sofia (BG); **Pencho Sirakov**, Sofia (BG); **Todor Penchev**, Sofia (BG); **Dimitar Mihaylov**, Sofia (BG)

(**) Term: **15 Years**

(21) Appl. No.: **35/511,747**

(22) Filed: **Apr. 12, 2021**

(80) **Hague Agreement Data**

Int. Filing Date: **Apr. 12, 2021**

Int. Reg. No.: **DM/213785**

Int. Reg. Date: **Apr. 12, 2021**

Int. Reg. Pub. Date: **Apr. 30, 2021**

(51) LOC (13) Cl. **08-08**

(52) U.S. Cl.

USPC **D8/391**

(58) **Field of Classification Search**

USPC D8/388, 391, 392, 393

CPC F16B 15/00; F16B 15/02

See application file for complete search history.
